UNITED STATES PATENT OFFICE

NATHANIEL G. WARTH, OF GALLIPOLIS, OHIO

AIRSHIP

Application filed September 19, 1927. Serial No. 220,423.

The principal object of the invention is to provide an airship of the rigid type, of the cigar form, that, as compared with those now in use is stronger, simpler, cheaper and lighter in its construction. In airships as formerly constructed, as far as I am aware, there is employed a keel, whereas in my construction I provide, generally speaking, a central longitudinal core or girder extending from end to end of the ship and about which, and connected with which is a series of spaced circular trusses standing transversely of the girder, and a series of longitudinal cables, under tension, extended over and attached to the rims of the trusses thereby providing spaces between such trusses for the gas cells. By my invention, as will duly appear from the detailed description herein the weights and stresses of the structure are centralized upon the longitudinal girder in a manner to cause the same to become a compression member restraining longitudinally all compression pressures and sustaining the circular trusses, the trusses in turn sustaining the longitudinal girder to prevent buckling thereof and assisting in maintaining its rigidity. The structure and the strength and lightness thereof may be likened in a broad way to a plurality of wire wheels mounted side by side on a single axle and tied together at their rims by a surrounding series of longitudinal cables under tension and connected at the opposite ends of the axle whereby the tensile strains of the cable are borne longitudinally by the single axle in compression.

The invention is embodied in the example herein shown and described.

In the accompanying drawings—

Figure 1 is a central vertical longitudinal section with some parts indicated in detail.

Fig. 2 is a transverse section on a larger scale showing one of the wheel-like circular trusses and the central girder.

Fig. 3 is a detail or plan view on a larger scale of a fraction of the rim of a circular truss.

Fig. 4 is an edge view of the same.

Fig. 5 is an end view of one of the transverse units forming the circular truss.

Fig. 6 is a detail of one method of spoking, the rim of the circular truss with the central girder.

Fig. 7 is a detail of the bow construction for mounting an engine and propeller. 55

Fig. 8 is a section on the line VIII—VIII Fig. 7 looking to the left.

Fig. 9 illustrates details of the construction for mounting the stern propeller.

Fig. 10 is a diagrammatic illustration of 60 a variation of the method of spoking a transverse truss rim to the central longitudinal girder.

Fig. 11 is a face view of one of the gas lifting cells on a very small scale. 65

In the instance shown the central longitudinal girder 11 is made up of three longitudinal 60 degree angle bars 12 cross latticed together to form an equilateral-triangle in end view. Around this longitudinal girder is arranged a series of equally spaced circular trusses 13 made up of short sections of girder each composed of the angle-bars latticed as described with reference to the central longitudinal girder 11, 75 and connected to one another at the outer side by a steel plate 15 as shown in Figs. 3 and 4 and at the inner angle by a V-shaped fish-plate 16 as shown in Figs. 4 and 5. These trusses stand at right angles to the 80 central girder and are of graduated diameters, they diminishing in diameter from the middle of the ship toward each end thereof in a manner to form substantially the rounding cigar shaped structure shown. 85

The circular trusses are all connected with the central girder by means of radial wire or cable spokes 14 that are attached to the trusses at their outer ends by looping the outer end of the spoke through two holes in the plate 15 and doubling the spoke back on itself and fastening it with a suitable clamp 17. The inner end of each spoke is attached in a similar manner, and by a clamp to a ring 18 through a hole in its rim encircling 90 and attached to the central longitudinal girder. These spokes are all drawn to a substantially uniform tension sufficient to maintain a substantially rigid relation of 95 the circular trusses to the central longitudinal 100 girder.

dinal girder. These circular transverse trusses take and sustain the stresses imposed on them in a manner similar to that in which the strains and stresses are borne and sustained by an ordinary wire wheel on its hub. To reinforce and better equalize the stresses borne by the radial spokes cross wires 19 on chords of arcs of the circular trusses are shown, these wires bracing the rim against compression or distortion. A modification of spoking is shown in Fig. 10 where the wires or cables extend from the angles of the longitudinal truss in various directions to the rim of the circular truss thereby if desirable eliminating the weight and expense of the rings 18.

The circular trusses are maintained in their proper transverse position by means of a series of cables 20 of high tensile steel wire stretched under strong tension between the stem and stern of the ship, the stem and stern ends of the central longitudinal girder being equipped with conical terminal members 21 and 22 respectively through holes in which the ends of the cables are looped and fastened with clamps as shown after the cables are drawn taut. The cables 20 are located equally distant apart around the periphery of the ship and are fastened to the rim of the circular trusses by securing them to the junction plates 15 by means of clamping plates 23, they being bound to said plates by bolts.

At the stern of the ship the angular bars 33 of the central girders are shown as converged into the conical member 22 and suitably secured thereto. Formed or secured in the said conical member 22 is a suitable bearing for the shaft of the stern propeller 25, said shaft and propeller being driven through bevel gears as shown by a suitable engine 26 located in the stern of the ship externally of the longitudinal girder.

At the bow of the ship the longitudinal girder is modified by omitting the terminal latticing therefor and affixing to the rings 18 a set of longitudinal ribs 27 latticed, to make room for an engine as shown at 28 and an attendant therefor. The crank shaft of the engine is suitably equipped for coupling it with the shaft 29 of the bow propeller 30, the propeller shaft being journaled in suitable brackets 31 and 32 attached to the forward end of the conical member 21. A hood 33 of semi-ovate form is provided at the end of the conical member 21 to close the bow and protect the engine and attendant against violent winds and the weather.

Between the longitudinal cables 20 are stretched and secured in a manner similar to that in which the cables 20 are secured intermediate cables or wires 35 for the purpose of reinforcing the strength of the structure and for affording additional sup-

port for the gas cells to prevent them from bulging beyond the frame. Further provision for confining the gas cells consists in shear wires 36 beneath which is placed gas cell wire netting, such as exemplified at 37, it being understood that, as usual, such supports are provided at all points wherever the bulging of the gas cells should be prevented.

Between the two middle transverse circular trusses are two series of guys 38 of cable similar to the longitudinal cables and of suitable number, said guys crossing each other and being connected at their outer ends to the longitudinal cables at the rim of one circular truss and at their inner ends to the central longitudinal girder in the plane of the opposite circular truss. The purpose of this construction is to provide an emergency terminal for each end portion of the ship so that if one end of the ship is crushed or damaged, as by collision, the other half is likely to remain intact and adapted to permit a safe landing.

There can be provided extending longitudinally of the ship at its bottom a corridor as indicated at 40 to which suitable entrances and exits are provided.

The gas cells 41, see Fig. 11, and shown in broken lines in Figs. 1 and 2, are made of substantially circular form with flat sides and having a radial slit or opening so that they can be placed between transverse trusses to straddle the longitudinal girder. The upper rim of the gas cells through 180 degrees is constructed of thin sheet metal to which the pendant fabric portions of the cell are attached with packing and riveting. The metal sheeting will be attached to the frame.

It will be observed generally that a very high degree of rigidity of construction is secured with my invention through the tautness of the longitudinal cables surrounding the hull, they pulling against the ends of the longitudinal central girder and bearing against the rims of the spaced transverse circular trusses, which in turn contribute to the stiffening of the longitudinal girder, through the connections with it, said longitudinal girder becoming a compression member. The cables are drawn sufficiently taut to secure the necessary general frame rigidity and develop a high degree of resistance through the tensile strength of the cables, contributed to by the uniformly distributed support of the equally longitudinally spaced circular trusses bearing directly against the central longitudinal compression girder throughout its length.

It will be understood, of course, that the ship can be constructed in the main of light strong material such for example as "duralumin" or such material as is generally used in the construction of air ships. It will also be understood that the ship will be equipped

with such accessories or features not particularly shown as may be needed in the ordinary operation and navigation of the same. The metal tops of the gas cells can take the place of the usual covering as to 5 their area of the hull.

It will be understood that ample weight will be added longitudinally to the lower portion of the ship tending to keep it trimmed, that is, in a general horizontal position with the corridor lowermost. 10

The forms, arrangement and details of the parts can be changed without departing from the gist of the invention as claimed.

What I claim is:

1. In an airship, a frame including a central longitudinal rigid unitary girder, transverse trusses secured at intervals to said girder, a plurality of longitudinal cables each extending from end to end of the girder and secured to the opposite ends thereof and supported on the rims of said transverse trusses and cable branches from said cables extending inclinedly therefrom and connected with the girder between adjacent 20 of said transverse trusses.

2. In an engine propelled airship, a frame including a central longitudinal rigid unitary girder, made up of latticed longitudinal bars, said bars extended unlatticed to the 30 forward end of the ship, a terminal member on said bars, a latticed frame of enlarged diameter around said bars to provide room for the engine and an attendant, a bracket secured to said terminal member to support the propeller shaft of the engine and also support the propeller beyond the forward end of the ship, and a hood enclosing the forward end of said engine room secured 35 between said propeller and said room.

3. In an air ship, a frame including a central longitudinal compression girder, transverse trusses secured at intervals to said girder, a plurality of longitudinal cables each extending straight away and under tension from end to end over the rims of said trusses and secured to the opposite ends of said girder, said cables initially freely movable from end to end for placing them under 45 tension on the rims of said trusses by overall tensioning, and distinct means for individually clamping each of said cables upon said rims after it has been placed under tension.

4. In an air ship, a frame including a central longitudinal girder, transverse trusses secured at intervals to said girder, and a plurality of continuous cables each extending straight away from end to end of said girder and secured under tension to the opposite 55 ends of the girder and supported on the rims of said transverse trusses, and means individual to said rims for clamping said tension cables to said rims.

5. In an air ship having a central longitudinal girder, transverse trusses at inter-

vals on said girder, and longitudinal cables supported in a tensioned condition on said trusses, a terminal member for said ship consisting of a single funnel shaped shell into the interior of the smaller portion of 70 which the longitudinal girder extends and is secured, the flared end of said funnel shaped member extending toward the body of the ship and having said longitudinal cables anchored thereto in a plane between the terminal of the longitudinal girder and the middle of the ship. 75

6. In an air ship, a frame including a central longitudinal girder, substantially circular trusses having hubs and rims and located at intervals between the ends of said girder, said trusses having tensioned spokes and supporting said girders from the rims of the trusses, and chord-like tensioned bracing members connecting some points of the 80 rims of said trusses with other points thereof. 85

7. In an engine propelled air ship, a frame including a central longitudinal girder, a housing forming a terminal of said girder, 90 a propeller beyond the end of the ship, a shaft for the propeller supported in said housing and an engine for driving said shaft, a propeller also supported in said housing. 95

8. In an engine propelled air ship, a frame including transverse trusses, longitudinal cables and a central longitudinal girder, enlarged at one end to form a housing, a propeller beyond the housing and a shaft for 100 the propeller supported by said housing and an engine for driving said shaft also supported by said housing, the other end of said longitudinal girder having a reduced end and a conical anchorage member thereon for 105 the longitudinal cables.

9. In an air ship having a central longitudinal girder provided with anchoring end members, transverse trusses at intervals on said girder, said trusses having rims and tensioned spokes and chord-like tensioned bracing members connecting some points of the rims of said trusses with other points thereof, a plurality of continuous cables extending straight away and tensioned over 110 the rim of said trusses and between and anchored to said end members of the longitudinal girder. 115

10. In an air ship having a central longitudinal girder provided with anchoring end 120 members, transverse trusses at intervals on said girder, said trusses having rims and tensioned spokes and chord-like tensioned bracing members connecting some points of the rims of said trusses with other points thereof, a plurality of continuous cables extending straight away over the rims of said trusses and under tension between and anchored to said end members of the longitudinal girder, and individual clamping mem- 125 130

bers securing said cables to said truss rims.

11. Inflating means for an air ship consisting of a plurality of removable units, each consisting of a top rim portion of sheet metal and constituting a gas restraining member adapted to form a section of the ship's external envelope, the other portions of said unit being of flexible fabric.

12. Inflating means for an air ship having a central longitudinal girder, said inflating means consisting of a plurality of removable units each comprising a top portion formed of sheet metal and constituting a gas restraining member and also adapted to form a section of the ship's external envelope, the other portions of said unit being of flexible fabric and provided with a recess permitting the straddling of said longitudinal girder when said unit is inflated.
